UNITED STATES PATENT OFFICE.

CHARLES BUSCHINO, OF LONG ISLAND CITY, NEW YORK, ASSIGNEE OF ONE-HALF TO
WILLIAM CHARLES ST. CLAIR, OF NEW ROCHELLE, NEW YORK.

INTERNAL-COMBUSTION ENGINE.

1,398,953.

Specification of Letters Patent. Patented Nov. 29, 1921.

Application filed October 2, 1919. Serial No. 327,844.

To all whom it may concern:

Be it known that I, CHARLES BUSCHINO, subject of the King of Italy, residing at 216 Jackson avenue, Long Island City, in the county of Queens and State of New York, have invented certain new and useful Improvements in Internal-Combustion Engines, of which the following is a specification:

10 This invention relates to internal combustion engines, and particularly to such engines in which sliding or reciprocating sleeves are used to control the admission of the combustible driving medium to the piston chamber and the exhaust of the burnt gases from such chamber.

The object of this invention is to provide an engine of this type which will be simple in construction and reliable in operation.

20 Slide-valve motors have certain advantages over puppet-valve motors, in that they avoid the noise and clatter which is incidental to the quick-closing of puppet valves, under the action of strong springs. Slide-25 valve motors, however, also have certain disadvantages, especially where the common arrangement of two sleeves is used. These sleeves generally move in opposite directions, and this results in considerable friction 30 between the two sleeves as well as between the inner sleeve and the piston, and between the outer sleeve and the surrounding cylinder casing, and there is therefore a considerable loss of power. Moreover, owing 35 to the fact that the reciprocating movement of the sleeve is effected by means of cranks engaging the sleeves at their lower ends, at one side thereof, there is a considerable strain on the parts, resulting in the frequent 40 breaking off of the lower ends of the sleeves.

It has been my aim to avoid the above-mentioned drawbacks, by providing a single sleeve to act as inlet and exhaust valve, thus 45 reducing friction to a considerable extent; this sleeve is closed at one end and forms a movable cylinder head, and it is reciprocated by cams arranged adjacent to the sleeve head and acting in the axis of recip-50 ration, thus avoiding the objectionable one-sided operation of the usual sleeve valves. These and other advantages will be clearly described in the specification following hereinafter, and the novelty will be 55 pointed out in the appended claims.

In the accompanying drawings, forming part of this specification, I have shown my invention applied to an internal combustion engine of the four-cycle explosion type; this is to be considered as an example only, and I do not wish to limit myself in any way to the details shown, but I desire it to be understood that various modifications may be made without departing from the nature of my invention.

In these drawings, Figure 1 is a vertical transverse section through one of the cylinders of my new motor; Fig. 2 is a top view of the motor, with the cover of hood removed; Fig. 3 is a partial section taken on line 3-3 of Fig. 1; Fig. 4 is a horizontal section taken substantially on line 4-4 of Fig. 1; and Figs. 5 to 8 inclusive are views illustrating diagrammatically four different steps of the operation of my motor.

The crank shaft 10 is suitably supported in the crank case 11 and has cranks 12 of usual arrangement each connected by a rod 13 to the corresponding piston 14. The cylinder casing 15, which is secured to the 80 crank case 11 and provided with the usual cooling jacket 16, is open at the end distant from the crank case (that is, its upper end) and in this cylinder casing is arranged movably, and co-axial therewith, a sleeve-valve 85 or cylinder 17 closed near its end remote from the crank case (that is, its upper end) by a transverse wall or head 18. The sleeve 17 and its head 18 inclose together the working chamber 19 in which the piston 14 reciprocates.

The cylinder casing 15 is formed with an inlet port 20 and an outlet port or exhaust port 21 lying preferably diametrically opposite each other and both at the same distance from the open end of the cylinder casing 15. These ports 20 and 21 are connected with the inlet and exhaust manifolds respectively, which are designated by the numerals 22 and 23. The sleeve 17 also is provided 100 with an inlet and an exhaust ports 24, 25 respectively, adapted to register at times with the ports 20 and 21. The ports 24, 25, however, are not exactly opposite each other, but are arranged at different distances from 105 the head 18 of the sleeve or cylinder 17, so that when, say, the port 24 registers with the inlet port 20, the port 25 is out of registry with the exhaust port 21, so that the latter is closed at that time, and vice versa. In 110

the example shown, the port 24 is arranged above the inlet port 20 (with the sleeve or cylinder 17 in the intermediate or "neutral" position) and the port 25 the same distance 5 below the exhaust port 21. Each of the ports 24, 25 extends for a considerable distance around the sleeve 17 (in the example shown about one-third of the circumference of the sleeve 17) and the ports 20, 21 in the 10 casing 15 are similarly arranged. These ports thus form narrow, but long slots, and allow a relatively large amount of fuel to enter, or of burnt gases to escape from, the working chamber in a relatively short space 15 of time.

Above the wall or head 18, the cylinder 17 is provided with an upward extension 17' having at its upper end an outwardly-extending flange 17" and inclosing a recess 26.

20 Secured rigidly to the head 18 as by bolts 27' is a housing 27 located partly in the recess 26 and adapted to contain a cam consisting of two sections, 28, 29, carried rigidly by a cam shaft 30 supported in bearings 31 25 (Figs. 2 and 3) bolted to the upper face of the cylinder casing 15. The housing 27 has at its portion adjacent to the head 18, a surface 27^a extending for about half the length of the housing (measured lengthwise of the 30 cam shaft) and engaged at all times by the cam section 28. The upper portion of the housing 27 opposite the surface 27^a is cut away or recessed as at 27^b, to form a clearance for the revolving cam section 28. Ad- 35 jacent to this recess 27^b the upper portion of the housing 27 has a surface 27^c engaged at all times by the cam section 29, and opposite this surface 27^c the lower portion of the housing 27 is cut away, as at 27^d, to pro- 40 vide a clearance for the cam section 29 during its revolution.

The cam section 28, by engaging the surface 27^a, pushes the housing 27 and therefore also the sleeve or cylinder 17, downward. 45 while the other cam section, 29, pushes it upward, and the cam surfaces of the two cam sections are so constructed that they will coact with each other, that is to say, the cam section 29, while remaining in contact with 50 the surface 27^c, will allow the housing 27 to move downward under the action of the cam section 28, while vice versa the cam section 28 remains in contact with the surface 27^a, when the housing moves upward under 55 the action of the cam section 29. Inasmuch as the planes containing the surfaces 27^a and 27^c of the housing are always at the same distance from each other, it follows that the 60 distance between tangential planes drawn on opposite sides of the cam shaft to different cam sections is constant.

The cam rotates in the direction indicated by the arrows, and each section is composed of several inclined and several 65 concentric or dwell portions. Thus, the cam

section 28 has in succession, an outwardly and rearwardly inclined portion 28^a, another portion, 28^b, also inclined outwardly and rearwardly, a concentric or dwell portion 28^c, a portion 28^d inclined inwardly and rearwardly, a concentric or dwell portion 28^e, and another, inwardly and rearwardly inclined portion 28^f, this latter connecting with the first-named portion 28^a. Similarly, the cam section 29 has a concentric or dwell 70 portion 29^a, an outwardly and rearwardly inclined portion 29^b, a concentric or dwell portion 29^c, an inwardly and rearwardly inclined portion 29^d, a similarly inclined portion 29^e, and an outwardly and rearwardly 75 inclined portion 29^f. Of these, the portions 28^a, 28^b, 29^b and 29^c are valve-shifting cam portions, while all the other cam portions are merely sleeve-holding portions, that is, they have the function of holding the sleeve 80 in a certain position and of preventing accidental movement, say under the action of the suction, compression, or explosion in the working chamber.

The cams 28, 29 may be separate or parts 90 of the same piece, but in any event, they are rigid with the cam shaft. For the purpose of proper operation, and in order to reduce wear, they run in oil which is supplied to the recess 26 in any suitable manner (say, by a 95 pump, not shown). Should too much oil be supplied, such surplus oil will run over the flange 17" which for this purpose is provided with grooves 17*, and drop into the recessed upper part 15' of the cylinder 100 casing 15, from where it runs into the crank case through tubes or ducts 32. The flange 17" prevents such oil from running down along the outside of the sleeve 17 and into the working chamber 19 where it would burn 105 with the fuel and thus cause "smoking" at the exhaust. The cylinder casing 15 is preferably provided with a cover or hood 33 which covers the moving or operating parts. This cover also serves to catch any oil 110 which may be thrown out of the recess 26 during the operation of the cams; this oil will run down the inside of the cover and into the recessed part 15' of the cylinder casing.

115 The spark plug 34 for igniting the fuel in the working chamber is preferably arranged in the side of the cylinder casing, and as shown in Figs. 1 and 4, its inner end registers with the inlet port 24 of the sleeve 120 or cylinder 17 when the latter is in its intermediate or "neutral" position shown in said figures.

The cam shaft 30 may suitably be driven from the crank shaft 10 in any convenient 125 manner, as by chains or gears, with the usual one to two ratio, that is to say, the cam shaft will make one revolution to every two revolutions of the crank shaft.

Four steps of the operation have been 130

illustrated diagrammatically in Figs. 5 to 8, and underneath each of these figures I have indicated diagrammatically the position of the crank and connecting rod corresponding to each cam and valve position shown in these figures, the circle 35 indicating the path of the crank pin 36, and the center of the circle indicating the crank shaft 10.

The operation is, briefly described, as follows: As indicated in Fig. 5, the piston has completed the exhaust stroke and is about to start on its suction stroke. The sleeve valve 17 has been brought to its neutral, or exhaust-closing position by the inclined cam surface 28^a acting on the surface 27^a of the cam housing 27. After a slight rotation of the cam shaft, the inclined surface 28^b comes in contact with the surface 27^a and pushes the valve sleeve down, so that the port 24 of 20 the valve comes into registry with the inlet port 20 of the cylinder casing, allowing the explosive medium to be sucked into the working chamber by the piston. The concentric cam portion 28^c holds the sleeve in 25 this position until after the crank pin has passed the lower dead center (see position illustrated in Fig. 6). During this time first the portion 29^a and then the portion 29^c of the cam section 29 have been in engagement with the surface 27^c of the housing 27 and have prevented the housing and valve sleeve from dropping farther than the position to which they have been brought by the cam section 28. After the crank pin has 30 passed the lower dead center, and just as the piston is about to start on its compression stroke, the sleeve valve is quickly moved to its neutral position, closing the inlet port 20, by the action of the cam portion 29^c on 35 the surface 27^c, the inwardly inclined cam portion 28^d coming in contact with the surface 27^a and allowing this movement. During the compression stroke of the piston which now follows, the concentric or dwell 40 cam portions 28^e and 29^a will be in contact with the surfaces 27^a and 27^c, respectively, and the cam portion 28^e will prevent the sleeve from being moved upward any further under the action of the compression in 45 the working chamber. This condition continues also during the explosion stroke of the piston, the position of the cam being indicated in Fig. 7. It will be noted that the position of the sleeve in this figure is the 50 same as in Fig. 5, that is, the sleeve is in its intermediate or neutral position.

As the piston nears its lowermost position, that is, before the crank pin reaches the lower dead center, the inclined cam portion 29^b lifts the sleeve valve, shifting it outward and bringing the port 25 into registry with the exhaust port 21 of the cylinder casing, thus allowing the burnt gases to escape into the exhaust manifold. This 55 position is shown in Fig. 8. The exhaust

remains open during the whole length of the exhaust stroke of the piston and is preferably closed only after the crank pin has passed the upper dead center, whereupon the sleeve valve is brought to its neutral position by the action of the cam portion 28^a on the surface 27^a, the inwardly-inclined cam portion 29^a allowing this movement, while remaining in contact with the surface 27^c. The same cycle of operation is then 75 repeated.

It will be noted that by my new arrangement I practically eliminate all friction beyond the usual amount existing between a piston and the cylinder in which it reciprocates. The extent of movement of the sleeve valve is very small, and very little power is required for the shifting of this valve. Moreover, this shifting either takes place in the same direction in which the piston moves 85 at that time, or the shifting is assisted by the conditions prevailing in the working chamber. Thus, to open the inlet, the sleeve moves inward, that is, in the same direction as the piston, and the suction exerted by the piston assists this movement. The closing of the inlet (outward movement of the sleeve valve) coincides with the upward movement of the piston and is assisted by the compression created by the piston in the working 90 chamber. To open the exhaust, the sleeve must move outward; while at this time the piston is practically at a standstill, the movement of the valve is assisted by the pressure still prevailing within the working 95 chamber. Finally, the closing of the exhaust port (inward movement of the valve sleeve) coincides with the downward movement of the piston and is assisted by the suction which the latter begins to exert in 100 the working chamber.

It is a further important advantage of my invention, that the power for shifting the sleeve valve is exerted axially, practically in the center line of movement of the sleeve, 110 instead of at one point of the sleeve's circumference, as with the usual two-sleeve arrangement. I thereby eliminate one of the serious drawbacks of sleeve-valve motors, as pointed out above.

The shifting of the sleeve valve by means of the cam takes place very quickly, and owing to the fact that the inlet and outlet ports are formed of narrow slots of large circumferential extent, a maximum amount 120 of driving medium can be admitted and a maximum amount of burnt gases exhausted in the short space of time available for these operations.

I claim as my invention:

1. In an engine, a stationary cylinder casing, a reciprocating piston located in said casing, a cylinder in sliding engagement with the piston and with said casing and interposed between them, said cylinder being 130

closed at one end to form a working chamber and having ports for the admission and exhaust of the driving medium, a cam located outside of said cylinder, adjacent to its closed end for operating said cylinder, a recess formed in said cylinder and adapted to contain lubricating oil for said cam, means at the upper end of said recess to prevent surplus oil from reaching the working chamber of the cylinder, and a collecting channel for said surplus oil in said cylinder casing.

2. An internal combustion engine, comprising in combination, a cylinder open at its upper end, a sleeve fitting within said cylinder and closed at its upper end, a piston fitting within said sleeve, a crank shaft to which said piston is connected, inlet and outlet ports in said cylinder controlled by reciprocation of said sleeve, cam means co-acting with the upper end of said sleeve to effect reciprocation thereof, operating means for said cam means, a recess in the outer end of said sleeve to receive oil for lubricating said cam means, and an outwardly extending flange at the upper end of said sleeve for preventing oil from said recess entering between the walls of the cylinder and sleeve.

3. An internal combustion engine, comprising in combination, a cylinder open at its upper end, a sleeve fitting within said cylinder and closed at its upper end, a piston fitting within said sleeve, a crank shaft to

which said piston is connected, inlet and outlet ports in said cylinder controlled by reciprocation of said sleeve, cam means co-acting with the upper end of said sleeve to effect reciprocation thereof, operating means for said cam means, a recess in the outer end of the sleeve forming an oil bath for said cam means, a collecting channel in the upper end of the cylinder, and an outwardly extending flange at the upper end of said sleeve having oil grooves for delivering excess oil from said recess to said channel. 45

4. An internal combustion engine, comprising in combination, a cylinder open at its upper end, a sleeve fitting within said cylinder and closed at its upper end, a piston fitting within said sleeve, a crank shaft to which said piston is connected, inlet and outlet ports in said cylinder controlled by reciprocation of said sleeve, cam means co-acting with the upper end of said sleeve to effect reciprocation thereof, operating means for said cam means, a recess in the outer end of the sleeve forming an oil bath for said cam means, a collecting channel in the upper end of the cylinder, an outwardly extending flange at the upper end of said sleeve having oil grooves for delivering excess oil from said recess to said channel, and conduits for conducting oil from said channel to the crank case of the engine. 55

In testimony whereof I affix my signature. 60
CHARLES BUSCHINO, 65
